TOY PYLON OR SIMILAR ARTICLE

Frank Pettit, Union, N. J.

Application September 16, 1957, Serial No. 47,754

Term of patent 14 years

(Cl. D34—15)

Fig. 1 is a perspective view of a toy pylon or similar article, showing my new design;

Fig. 2 is a top plan view, to an enlarged scale;

Fig. 3 is a side elevational view, to an enlarged scale; and

Fig. 4 is a cross-sectional view thereof, to an enlarged scale, taken along line 4—4 of Fig. 3.

The broken line showing of an airplane and supporting rod in Fig. 1 is for illustrative purposes only.

What is claimed is:

The ornamental design for a toy pylon or similar article, substantially as shown and described.
